UNITED STATES PATENT OFFICE.

JOHN W. RAMIGE, OF ONTARIO, CALIFORNIA.

AUTOMATIC STATION-INDICATOR.

1,072,772.

Specification of Letters Patent. Patented Sept. 9, 1913.

Application filed September 23, 1912. Serial No. 721,729.

To all whom it may concern:

Be it known that I, JOHN W. RAMIGE, a citizen of the United States, residing at Ontario, in the county of San Bernardino, State of California, have invented certain new and useful Improvements in Automatic Station-Indicators; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in railway trains and electric cars and particularly to an attachment therefor adapted to automatically indicate the next succeeding station just after a train leaves one station, which indicator will obviate the necessity of the conductor of the train calling the name of the station as is now the common practice.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claim.

On the drawings similar characters of reference indicate corresponding parts in the several views.

Figure 1 is a sectional view of a fragmentary portion of a car showing the relative position of my improved indicator and its operating means on said car. Fig. 2 is a front elevation of the indicator itself. Fig. 3 is a sectional view showing a roller and gear connecting means.

Referring now more particularly to the characters of reference on the drawings, the numeral 1 designates the car, the numeral 2 the wheels and the numeral 3 designates the ordinary rails upon which the wheels roll.

The numeral 4 designates a box or casing for the indicator proper in which are disposed two rollers 5 and 6 spaced apart and being provided with spaced pairs of shoulders 8 and 9 respectively.

The numerals 10 and 11 designate expansive springs interposed between a shelf 12 on the side of the box 4 and each of the rollers 5 and 6 respectively for the purpose

of holding a roll or sheet 13 always in frictional contact with said rollers and between the shoulders 8 and 9, on which sheet 13 are imprinted designating means 14 to indicate and designate the several stations through which the train will pass.

Secured on the end of the roller 6 by means of a thumb screw 15 is a sleeve 16 provided on its end with a beveled gear 17 which intermeshes with another beveled gear 18 on a vertical shaft 19. On the lower end of the shaft 19 is another beveled gear 20 intermeshing with still another beveled gear 21 mounted on a shaft 22 disposed horizontally underneath the body of the car 1. A universal joint connects the shaft 23 with an inclined shaft 24 projecting through a guide 25 and provided with a wheel 26 on its outer end.

Disposed along the side of one of the rails 3 near each station is an auxiliary independent piece of rail 27 upon which the wheel 26 is adapted to ride. The length of said rail 27 is sufficient so that the revolution of the wheel 26 over the same will, through the gear and shaft mechanism described, turn the sheet 13 a sufficient distance to display the next succeeding station designation thereon into view. The wheel 26 is held in frictional contact with the rail 27 by means of an expansive spring 28. When it is desired to raise the wheel 26 away from contact with the rail 27, I provide a rod 29 engaged with the shaft 24 and projecting through the body of the car to a convenient point and provided with a hook 30 adapted to be engaged with a pin 31. This mechanism may be used at such times as when it is desired to back the train or under similar circumstances. Each of the rollers 5 and 6 is provided with a square end in order to receive a turning knob 32 for turning the sheet 13 in one direction or the other. When it is desired to turn the sheet 13 backward the thumb screw 15 is loosened in order that the roller 6 may be rotated without turning the entire mechanism.

From the foregoing description it will readily appear that since the length of the rail 27 corresponds with the distance between the station designation on the sheet 13, this causes such sheet to move up to display the proper station each time the wheel 26 rides on one of the rails 27.

From the foregoing description it will

readily appear that I have produced such a device as substantially fulfills the objects of the invention as set forth herein.

While this specification sets forth in detail the present and preferred construction of the device, still in practice such deviations from such detail may be resorted to as do not form a departure from the spirit of the invention.

10 Having thus described my invention what I claim as new and useful and desire to secure by Letters Patent is:

A device of the character described comprising the combination with a railway car 15 mounted on rails, of a rail section disposed independently of the rails upon which said car is mounted, a shaft swung under said car and capable of moving vertically there-

under, a wheel on one end of said shaft adapted to ride on said independent rail section, a spring interposed between the bottom of said car and said shaft to hold said wheel in engagement with said independent rail section, a rod on said shaft projecting into said car, a catch on said car adapted to 25 be engaged by said rod to hold said wheel out of engagement with said rail section, and a station indicating mechanism flexibly connected with said shaft, as described.

In testimony whereof I affix my signature 30 in presence of two witnesses.

JOHN W. RAMIGE.
